UNITED STATES PATENT OFFICE

161,228

BOWL

Carl Wilkerson, Arcata, Calif.

Application May 10, 1948, Serial No. 146,254

Term of patent 14 years

(Cl. D44—10)

To all whom it may concern:

Be it known that I, Carl Wilkerson, a citizen of the United States of America, residing at Arcata, in the county of Humboldt and State of California, have invented a new, original, and ornamental Design for a Bowl, of which the following is a specification, reference being had to the accompanying drawing, forming a part thereof wherein:

I claim:

The ornamental design for a bowl, as shown.

CARL WILKERSON.
